UNITED STATES PATENT OFFICE.

JOSIAH H. ROHRER, OF PHILADELPHIA, PENNSYLVANIA.

FEED-WATER HEATER.

Application filed January 9, 1923. Serial No. 611,569.

To all whom it may concern:

Be it known that I, JOSIAH H. ROHRER, a citizen of the United States, and a resident of Philadelphia, in the county of Philadelphia and State of Pennsylvania, have invented certain new and useful Improvements in Feed-Water Heaters, of which the following is a specification.

The most efficient method of generating steam in a water-tube boiler is to separate the heating of the water in the boiler into two separate steps or stages which, considered from the viewpoint of raising the water from feed-water temperature to boiling temperatures, consists of (1) pre-heating the feed-water and (2) the conversion of the water into steam.

For these purposes boilers, particularly of the water-tube type, are generally arranged so that the hot gases of combustion from the grate or fire-box first go over or pass in and between the banks of tubes comprising the steam-generating stage or section, and thereafter the gases, which have lost heat in the steam-generating section, are conducted over, through and around one or more banks of tubes comprising the pre-heater or economizer section or stage, and in passing through the economizer section the temperature of the gases of combustion are further reduced, so that as little heat as possible is lost in the stack or chimney. It must be apparent, therefore, that the temperature of the water in the pre-heater or economizer section must be substantially below the boiling temperatures and considerably below the temperature of the partially cooled gases passing thereover in order that the water in the pre-heater or economizer may absorb heat from the partially cool gases and may not boil. If the temperature of the water in the economizer section were high, then the gases would pass over and through the economizer tubes without substantial reduction in the temperature. The temperature of the gas leaving the economizer and entering the stack would be higher than is necessary or economical, and steam would be generated in the economizer. Such an operation of a boiler would be wasteful and inefficient. It must therefore be plain that the temperature of the water in the economizer section must be kept relatively low in order to absorb heat from the gases of combustion passing therethrough.

There is another consideration in steam boiler construction and operation which is also of great importance. Feed water, unless specially treated or purified, contains a great deal of oxygen in the form of air, and if feed-water, with oxygen dissolved therein, be fed to the boiler and then heated the oxygen is freed. If this free oxygen could be conducted directly out of the boiler it would have very little, if any, injurious effect on the steel boiler tubes, but it has been the usual practice to deliver the feed water to the economizer or pre-heater, before its actual delivery to the steam-generating section of the boiler. Now, the economizer section does not generate steam, and hence the oxygen which is liberated from the feed-water in the economizer is not driven off, but collects in the top drum of the economizer section. Here it rapidly corrodes the interior walls of the economizer drum, because the economizer drum is practically always filled with it. The economizer section therefore deteriorates much more rapidly than does the steam generating section of the boiler.

To free fresh feed-water from the deleterious gases contained therein, it is necessary to raise the temperature of the water to substantially boiling temperatures, but if the feed-water, at boiling temperatures, were to be admitted directly to the economizer, then the temperature of the body of water in the economizer would be so raised that the economizer would form a steam-generating section which would not sufficiently reduce the temperature of the gases passing to the flue or stack. To raise the temperature of the feed-water to boiling temperatures to drive off the deleterious gases, and to then cool it to economizer temperatures, before admitting it to the boiler structure would also be obviously wasteful.

The object of my invention is to provide a construction wherein the temperature of the incoming feed-water is raised by the boiler to temperatures at which deleterious gases are expelled; wherein the said expelled gases are conducted away from the feed-water prior to its admission into the economizer section; and wherein the relatively cool incoming feed-water is used to abstract heat from the purified feed-water to reduce the temperature of the feed-water back to economizer temperatures. In other words, it is my object to provide a pre-heater and water-

purifier wherein there is an exchange or interchange of heat during the operation of the device; wherein the temperature of the cool incoming feed-water is raised 5 to substantially boiling temperatures for the purpose of freeing it from injurious gases, and wherein the temperature of the purified feed-water is then cooled by 10 passing it over and around the incoming feed-water conduit, so that the purified water heats the incoming feed-water and conversely, the cool incoming feed-water lowers the temperature of the purified water back to economizer temperatures.

15 It is the object of my invention to provide an arrangement wherein an interchange of heat within the boiler structure may be effected to free the feed-water of deleterious gases and keep the temperatures of the 20 economizer section of the boiler down to such a point that the water in the economizer may abstract heat from the gases of combustion passing thereover in substantially as efficient a manner as this is accomplished wherein the 25 feed-water is not so purified.

Other objects of my invention will appear in the specification and claims below.

Referring now to the drawings forming a part of this specification and in which the 30 same reference characters are employed throughout the various views to designate the same parts, Fig. 1 is a vertical, longitudinal section through a water-tube boiler showing the steam-generating section or the 35 economizer or pre-heater section and the passage of the products of combustion in and between the tubes through the two sections of the boiler, said boiler being provided with my improved feed-water heater and purifier;

40 Fig. 2 is a longitudinal vertical sectional view through the purifier shown in Fig. 1 and on a larger scale than that employed in Fig. 1, said purifier being shown attached to the upper drum of the economizer, the latter being 45 shown substantially in elevation except that parts are broken away to show the interior of one end of the economizer drum;

50 Fig. 3 is a modified form of my invention, the purifier being mounted within the upper drum of the economizer;

Fig. 4 is another modified form of my invention wherein the feed-water is admitted directly to the steam-generating section of the boiler, and the conduit for the feed-water 55 passes through a chamber through which water from the boiler is supplied to the economizer; and

60 Fig. 5 is a still further modification of my invention wherein the feed-water is discharged directly into the steam-and-water drum of the boiler, and the water, circulating from the boiler to the economizer, surrounds the feed-water pipe and is cooled by the incoming feed-water.

65 Referring first to the embodiment of my

invention as illustrated in Figs. 1 and 2, the water-tube boiler preferably consists of an outer casing or housing 1 within which is set the steam-and-water drum 2, the water-drum 3 and the lower or mud-drum 4. A 70 bank of tubes 5 connects the steam-and-water drum with the water-drum 3; a bank of tubes 6, connects the water-drum 3 with the mud-drum 4; and a bank of tubes 7 connects the steam-and-water drum 2 with the mud-drum 75 4. In the front of the boiler is the live-steam header 8 which is connected with the steam-and-water drum 2 by a bank of super-heater tubes 9. Baffling 10 is arranged to cause the gases of combustion from the firebox 11 to 80 pass first lengthwise of and then through the bank of tubes 6; then vertically through the bank of tubes 5 up into the chamber adjacent the header 8 and superheater tubes 9; then back through the upper bank of tubes 5, and through the upper half of the bank of tubes 5. To the rear of the bank of tubes 7 is preferably arranged baffling 12 which directs the gases of combustion coming through the upper half of the bank of tubes 7 to 90 strike against the upper end of the economizer tubes 13. The upper ends of these economizer tubes 13 are connected and communicate with the upper drum 14 of the economizer, and the lower ends of said tubes 95 13 are similarly connected to the lower drum 15 of the economizer. In the middle of this bank of tubes 13, a baffle 16 preferably extends from the upper drum 14 downwardly toward the lower drum 15, so that the hot 100 gases striking the upper end of the bank of tubes 13 on one side of the baffle 16 are deflected downwardly along the tubes 13 toward the lower drum 15, then passing around the lower end of the baffle 16 pass upwardly lengthwise of the economizer tubes 13 on the opposite side of the baffle 16, and then out of the boiler through the passage 17 to the stack. A bank of tubes 18 preferably 105 connects the upper economizer drum with the steam-and-water drum 2. This bank of tubes 18 is preferably below the water-lines which are maintained in the steam-and-water drum and in the economizer section, so that water may freely pass from the economizer 110 drum 14 to the steam-and-water drum 2 to replace such water as may be converted into steam in the boiler section.

An upper bank of tubes 19 also preferably connects the upper portion of the drum 14 115 with the upper portion of the steam-and-water drum 2 to maintain an equality of steam-pressure in the two drums.

The above is substantially the type of water-tube boiler to which my invention is 120 particularly adapted. The drums 2, 3, 4 and 8 and the banks of tubes 5, 6, 7 and 9 with the baffling 10 and 12 above described constitute the steam-generating section A of the 125 boiler, while the drums 14 and 15 with the 130

connecting bank of tubes 13 and baffles 16 and the banks of tubes 18 and 19 above described constitute the economizer or preheating section B of the boiler. The boiler then 5 substantially consists of the steam-generating section A and the economizer section B.

Now, if impure feed-water, that is to say, feed-water which has dissolved therein oxy- 10 gen or gases which corrode or chemically attack the interior of the water-tubes of the boiler, were to be admitted, as it frequently is, directly to the economizer section B and there heated sufficiently to expel the dele- 15 terious gases contained in the feed-water, those gases will accumulate above the water-line in the drum 14. The pipes or tubes 19 are pressure-equalizing pipes. No substantial amount of steam is generated in the econo- 20 mizer section B, and, therefore, these deleterious gases collect and are retained in the drum 14 and have time to injuriously act on the interior of the said drum 14. It is to obviate this undesirable condition that my 25 invention is directed.

It is proper to here make plain another action which must be considered in connection with the problem of pre-heating feed-water. The temperature of the water in the 30 economizer section B must be considerably lower than the water in the boiler section A. As the gases of combustion pass through the steam-generating section, the temperature thereof is considerably reduced. But the 35 gases are yet very hot. It would be uneconomical to pass these gases directly to the stack. The economizer is for the purpose of abstracting more heat from the partially cooled gases by absorbing that heat into 40 the water being supplied to the boiler or steam-generating section through the economizer. If therefore the temperature of the water in the economizer B is not relatively low as compared with the temperature of the water in the boiler heat is not abstracted 45 from the gases passing through the economizer. Thus it is that deleterious gases may be driven out of feed-water by raising the temperature of the water to boiling 50 point, but to admit this purified water at boiling temperature directly into the economizer would defeat the very purpose of the economizer, because it would so raise the temperature of the water in the economizer 55 that steam would be generated in the economizer. The economizer section B would then be a steam-generating section of the boiler, instead of a preheater, and heat would not be sufficiently abstracted from the 60 gases coming to the economizer from the steam-generating section. If deleterious gases were to be expelled from feed-water by raising the temperature of the water to boiling temperatures, then that water would 65 have to be cooled again to cause it to operate

efficiently in the economizer. This energy expended in heating the feed-water by the boiler and then cooling it independently of the boiler, to bring back to economizer temperatures would result in loss and waste of 70 energy, and a decrease in the efficiency of the boiler. In my construction, however, I raise the temperature of feed-water to boiling temperatures, and then effect an interchange or transfer of heat, all within the 75 boiler structure, so that the water delivered from the purifier is reduced to a temperature at which the economizer may operate efficiently, and without imposing any additional work on the boiler or detracting from the efficiency of the boiler. I transfer heat from one part of a boiler to another part of the boiler without any substantial loss of energy. 80

In the form of my invention illustrated in 85 Figs. 1 and 2, I therefore provide a drum 20 preferably mounted above the economizer drum 14 and above the boiler-housing or casing 1, and within this drum I mount one or more series of shallow pans 21, one above 90 the other, so arranged that when one pan is filled to overflowing with water, the water falls into the pan next below it. This series of pans may be supported within the drum 20 in any suitable manner, as, for instance, being secured to straps 22 depending from the top of the drum 20. 95

Mounted also within the drum 20 and at or near the bottom thereof and extending longitudinally thereof, are a set of U-tubes 23 or tubes having a return bend, the opposite ends of which are attached respectively to a header 24 having a partition 25 therein dividing the header into compartments. In this way each tube will have one end communicating with the compartment of the header on one side of the partition 25 and its other end communicating with the compartment in the header on the opposite side of the partition 25. 100

The lower compartment of the header 24 is preferably connected by a pipe 26 passing through the head of the drum 20 and this pipe 26 constitutes the intake pipe through 105 which raw or unpurified feed-water is taken into the purifier drum 20. 115

The other compartment in the header 24 is preferably connected to a pipe or riser 27 which extends to the top of the header 20 and then, passing lengthwise of the drum 20, is preferably provided with spraying nozzles 28-28, one for each set of pans 21. 120

Below the pans 21, preferably extends a partition or separator plate 29, inclined toward the header 24 so as to cause water falling thereon to flow toward said header 24. Below the partition 29 are arranged a series of transverse baffles 30-30-30 preferably arranged in staggered relation, as is shown 125 in Fig. 2, and adjacent the bent ends of the 130

U-tubes 23 is arranged another transverse partition 31 forming a dam having a horizontal top edge a little below the highest part of the partition or separator plate 29. 5 The end of the header or drum 20 which is to the right of the partition or dam 31 is preferably connected by a pipe 32—32 to the economizer drum 14, and is preferably provided with a valve 33 for the purpose of controlling the flow of water from the drum 20 to the drum 14.

Referring now to Fig. 1, I preferably connect the drum 20 with the steam-and-water drum 2 by a pipe 34 also preferably provided with a valve 35, to admit live steam from the steam-drum 2 to the drum 20 above the level of the water therein.

I preferably attach a pipe 36 to the top of the drum 20 and preferably tap in another 20 branch pipe 37 just above the level of the water in the drum 20, these pipes forming the means by which the gases, separated from the water in the drum 20, are conveyed away. These gases may be used to 25 run a pump or compressor, or to perform any other useful work.

To the bottom of the drum 20 I preferably attach a blow-off pipe 38 by means of which any accumulation of mud or sediment in 30 the bottom of the tank 20 may be expelled from the drum by opening the valve 39. (See Fig. 2.)

The operation of the embodiment of my invention is as follows: Feed-water is admitted to the drum 20 through the pipe 26. 35 It passes into the lower compartment of the header 24, and then through the lower-branch of the U-tubes 23 to the upper compartment of the header 24, then through 40 the riser 27 to the nozzles 28 where it is preferably sprayed into the top pans of the series of pans 21. When the top pans are filled, the water overflows their edges, and drops or trickles down into the pan 21 next 45 below, and so through the series of pans to the last pan. From this last pan the water overflows and falls to the inclined partition 31 and thence to the bottom of the tank 20 on the left hand side of the dam 31. The 50 partition 29 gives this water a movement to the left toward the header 24 and in course of time the bottom of the tank 20 will be filled with water up to the top horizontal edge of the partition or dam 31. The edge 55 of this partition 31 is high enough to produce a depth of water in the drum 20 sufficient to fully cover the U-tubes 23 and header 24.

After the water has risen to the top of the 60 dam or partition 31 it trickles over the edge of the dam and falls to that part of the drum 20 to the right of the dam 31 and from this the water is conducted through the pipe 32 to the economizer drum 14.

65 In falling from pan to pan, the water is

brought into intimate contact with live steam admitted to the top part of the drum 20 through the pipe 34 from the steam-and-water drum 2. It is live steam at boiler pressure and temperature that is admitted 70 to the top of the drum 20 and this serves to raise the temperature of the water as it falls from pan to pan up to substantially boiling temperature. This serves to disassociate from the water the deleterious gases 75 dissolved therein. These gases may be lighter or heavier than steam. For that reason I have provided the pipe 36 which communicates with the top of the drum 20 with the branch 37, which is just at the 80 water level in the drum 20 so that the deleterious gases may be driven off substantially as fast as they are liberated whether they be heavier or lighter than steam.

Now, as above pointed out it would detract from the efficiency of the boiler if the hot water at boiling temperatures in the pans 21, or as delivered from the series of pans 21, were to be conducted to the economizer section. Efficient operation of the 85 boiler requires that the water thus freed from deleterious gases be cooled back to a temperature low enough to operate efficiently in the economizer, to abstract heat from the gases of combustion passing through 90 the economizer. This is what my invention accomplishes, and in the following manner: The U-tubes 23 are submerged in the water which is discharged from the series of pans. It is through this hot water that the 95 relatively cold feed water is circulated. The cool feed-water enters the header 24 through the pipes 26, circulates through the U-tubes 23 and reduces the temperature of the purified water. In doing this, of course, the 100 temperature of the incoming water is correspondingly raised by the absorption of heat from the water outside of the pipes 23. This action constitutes then an interchange 105 of heat without substantial loss. The cool feed-water, from the moment it enters the drum 20 begins to accumulate heat from the purified water surrounding it, and conversely, the hot purified water accumulating in the bottom of the tank 20 is giving up its 110 heat to the incoming water, with the result that its temperature is being reduced to temperatures at which it may efficiently operate in the economizer section B.

115 In Fig. 3 I have shown a modified form of purifier in that the purifier is mounted directly within the top economizer drum 14. The feed pipe 26 is admitted directly into the top drum 14 of the economizer and communicates with a coil 23', submerged below the top of the level of the water in the economizer drum 14. From the coil 23' a riser 27^a extends to substantially the highest point in the drum 14 and its end is provided 120 with one or more nozzles 28 over one or 125

more series of pans 21—21—21, all inside of the economizer drum 14 and above the level of the water therein. Under the pans 21 is an inclined partition 29', the inclination of which is such as to cause the water falling thereon from the pans or trays 21 to circulate over to the coils 23'. A partition 31' serves to cut off or separate the coil 23' from the main or body portion of the drum 14. 5 This partition 31' is, however, preferably provided with holes 32' in the bottom thereof. A pipe 37 communicates with the interior of the drum 14 just above the water level for the purpose of conveying away the 10 separated gases.

In this modified form of my invention, the regular bank of pipes 19 extending between the steam-and-water drum 2 and the upper drum 14 of the economizer replaces the special pipe 34 previously described. Through 15 this pipe or series of pipes 19 live steam is conveyed to the top of the economizer section. Water entering through the inlet pipe 26 and coils 23' passes to the top of the drum 14 through the riser 27^a and then is sprayed in the top pan of a series of pans 21. Falling over the edges of these pans from one pan to the next, the water finally falls on the inclined partition 29' and runs into the 20 chamber formed by the wall or partition 31' and around the coil 23'. This water then passes over the coils 23' and heat is absorbed therefrom by the cold water entering the drum through the pipe 26. The interchange 25 of heat takes place in this form or embodiment of my device all within the drum 14. The cool water, after it has passed downwardly over the coils 23', passes through the holes 32' in the partition 31' and commingles 30 with the water which is circulating in the economizer section. In this instance this cold feed-water serves to keep the temperature of the water in the economizer to a low working temperature and the steam in the 35 top of the drum 14 heats the feed water as it drops from pan to pan sufficiently to drive the deleterious gases dissolved therein out of the water, and the said gases are conducted away from the drum 14 through the pipe 37.

40 In Fig. 4 I provide within the boiler structure a closed box or drum 20' within which is a coil 23' communicating with the feed-water inlet-pipe 26. The other end of the coil 23' is attached by a pipe 27^b to the lower 45 or mud drum 4 of the steam-generating section of the boiler. The lower drum 15 of the economizer is attached by a pipe 35 to the chamber 20'. Below the level of the water in the steam-and-water drum 2, a pipe 50 56' extends to a water circulatory pump 37' and this pump is connected by a pipe 38 with the interior of the water purifying box or drum 20'. The operation of this form of my invention is as follows: Feed water admitted through the pipe 26 passes through the coil 23' and thence by the pipe 27^b is discharged directly into the coolest part of the boiler. This incoming cool water is used to keep down the temperature of the water in the economizer section B by pumping hot 70 water from the top of the boiler down to, through and over the coils 23' and thence through the pipe 35 to the economizer section B. In passing through the coil 23' the temperature of the feed-water is raised to 75 substantially boiling temperatures and any deleterious gases which may be separated therefrom as bubbles will be carried along with the purified water to the mud drum 4 through the pipe 27^b. These gases immediately rise through the banks of tubes in the boiler section to the steam-and-water drum 2 whence they are immediately carried away with the steam which is being generated. 80 The driving off of any gas which may remain in the feed-water entering the drum 4, is accomplished in the boiler itself. In this form of my device then, the temperature of the feed-water is raised to substantially boiling temperatures and is delivered directly 85 to the boiler section or steam-generating section A of the boiler, but the temperature of the economizer is kept low by pumping or circulating water supplied thereto from the steam-generating section, over the coils 23', 90 where through which the cold incoming feed-water is conducted.

In Fig. 5 I have shown a still further modified form of my invention. In this instance, the top of the steam-and-water drum 2 is provided with a series of troughs or pans 21' all arranged so that as the top pan is filled, the water falls to the pan or trough below it and so on through the series of pans. 95 These pans are located above the level of the water in the boiler. The feed-water pipe 26 communicates with a coil 23' in a drum or compartment 20' and passing therethrough is delivered by a pipe 27^c to the top 100 of the steam-and-water drum 2 whence it falls through the pans in intimate contact with the live steam in the boiler; its temperature is raised to boiling temperatures and the gases dissolved therein are separated 105 therefrom. The drum 20' is located between the steam-and-water drum 2 and the economizer drum 14. One end of the drum 20' is preferably attached by a pipe 35' to the economizer drum 14 below the normal water level thereof and the other side of the drum 20' is connected by a pipe 38' with the interior 110 of the steam-and-water drum 2 below the level of the water therein. Immediately below the edge of the lowest of the pans or troughs 20' in the drum 2, a partition 31'' 115 is arranged extending lengthwise of the drum and this partition is attached to the inside of the drum below the pipe 38'. The operation of this form of my invention is as follows: Cold unpurified feed-water is admitted 120 through the pipe 26 passes through the coil 23' and thence by the pipe 27^c is discharged directly into the coolest part of the boiler. This incoming cool water is used to keep down the temperature of the water in the economizer section B by pumping hot 125 water from the top of the boiler down to, through and over the coils 23' and thence through the pipe 35' to the economizer section B. In passing through the coil 23' the temperature of the feed-water is raised to substantially boiling temperatures and any deleterious gases which may be separated therefrom as bubbles will be carried along with the purified water to the mud drum 4 through the pipe 27^c. These gases immediately rise through the banks of tubes in the boiler section to the steam-and-water drum 2 whence they are immediately carried away with the steam which is being generated.

ted through the pipe 26 and through the coils 23' and through pipe 27° to the top of the steam-and-water drum 2 and is caused to fall from one pan to the pan next below it in intimate contact with the live steam in the drum 2, to raise the temperature of the feed-water to boiling temperatures and to disassociate therefrom the deleterious gases. From the last or lowermost trough or tray 10 21' the water falls into the compartments formed by the wall or partition 31" and passes through the pipe 38', through the drum 20', over the cooling coils 23', to the top drum 14 of the economizer through the 15 pipe 35'. In this way the heated and purified water is cooled by its passage over the coils 23' through which the cold water is entering the boiler. The gases which are thus freed from the feed-water and which 20 are generally heavier than the steam, tend to accumulate just above the surface of the water in the drum 2 but they are immediately carried away with the steam through the superheater tubes 9. There is no substantial 25 transfer of steam from the drum 2 to the drum 14 through the pipes 19. These pipes 19 merely serve to equalize the pressure in the two sections or stages of the boiler, and therefore the deleterious gases 30 do not pass from the drum 2 to the drum 14.

In all of these embodiments of my invention there is a mere transference of heat from one part of the boiler to another but without loss. The heat that is put into the feed 35 water to raise it to boiling temperatures in order to disassociate therefrom the deleterious gases is abstracted from the purified feed-water by passing it over coils through which the cold incoming water is being supplied to the purifier. There is no substantial 40 loss of energy. The deleterious gases are entirely removed. The life of the boiler and of the economizer is substantially lengthened and the efficiency of the boiler is 45 maintained.

Having thus described my invention, what I claim and desire to protect by Letters Patent of the United States is:

1. In a boiler comprising a steam-generating section and an economizer section, the 50 combination of a heat-conductive feed-water conduit through which relatively cold feed-water is caused to flow, means to transfer heat from said steam-generating section to said feed-water after said feed-water has 55 passed through said heat-conductive conduit to raise the temperature of said feed-water to boiling temperatures to purify the same by separating deleterious gases therefrom, means to conduct hot purified water, so formed, over said heat-conductive conduit to reduce the temperature of the purified water to economizer temperatures, and means to conduct said purified water, so

formed, to said economizer, after it has 65 passed over said heat-conductive conduit.

2. In a boiler comprising a steam-generating section and an economizer section, the combination of a heat-conductive feed-water conduit through which relatively cold 70 feed-water is caused to flow, means to transfer heat from said steam-generating section to said feed-water after said feed-water has passed through said heat-conductive conduit to raise the temperature of said feed-water to boiling temperatures to purify the same separating deleterious gases therefrom, means to conduct hot purified water, so formed, over said heat-conductive conduit to raise the temperature of the cool water, 75 in said conduit and to reduce the temperature of the purified water to economizer temperatures, and means to conduct said purified water, so formed, to said economizer, after it has passed over said heat-conductive conduit.

3. In a boiler comprising a steam-generating section and an economizer section, the combination of a feed-water purifier having a heat-conductive feed-water conduit there-in in communication with a suitable source or relatively cool feed-water, means to transfer heat from the said steam-generating section to said purifier to raise the temperature of said feed-water to substantially boiling temperatures to purify said feed-water by separating deleterious gases therefrom, means to conduct hot purified water over said heat-conductive conduit to effect a transference of heat from said hot purified water to said relatively cool feed-water in said conduit and to reduce the temperature of said purified water to temperatures below boiling temperatures, and means to convey purified water to said economizer after it has passed over said heat-conductive conduit.

4. In a boiler comprising a steam-generating section and an economizer section, the combination of a feed-water purifier having a length of metal therein forming a cool feed-water intake pipe, means to transfer heat from the said steam-generating section to said feed-water in its passage through said purifier after it has passed through said intake pipe to raise the temperature of the water to substantially boiling temperatures to separate deleterious gases therefrom, means to conduct hot purified water over and around said intake pipe whereby cool incoming feed-water in said pipe is operative to reduce the temperature of said hot feed-water to temperatures substantially below boiling temperatures, and means to deliver to said economizer said feed-water after it has flowed over said intake pipe.

5. In a boiler comprising a steam-generating section and an economizer section, the combination of a feed-water purifier having

- a length of metal therein forming a cool feed-water intake pipe, means to transfer heat from the said steam-generating section to said feed-water in its passage through
- 5 said purifier after it has passed through said intake pipe to raise the temperature of the water to substantially boiling temperatures to separate deleterious gases therefrom, means to conduct hot purified water over
- 10 and around said intake pipe whereby cool incoming feed-water in said pipe is operative to reduce the temperature of said hot feed-water to temperatures substantially below boiling temperatures and said hot feed-water raises the temperature of said feed- 15 water in said intake pipe, and means to deliver to said economizer said feed-water after it has flowed over said intake pipe.

In witness whereof, I have hereunto set my hand this eighth day of January, 1923.

JOSIAH H. ROHRER
